C. DORNIER

STRUCTURAL FRAMING

Filed June 28, 1920

Inventor:

Claudius Dornier.

UNITED STATES PATENT OFFICE.

CLAUDIUS DORNIER, OF FRIEDRICHSHAFEN, GERMANY.

STRUCTURAL FRAMING.

Application filed June 28, 1920. Serial No. 392,543.

To all whom it may concern:

Be it known that I, CLAUDIO DORNIER, a citizen of the German Empire, residing at Friedrichshafen, Germany, have invented 5 certain new and useful Improvements in Structural Framing, of which the following is a specification.

My invention relates to an improved type of section rods or flanged channel irons 10 forming structural units, and to framings composed thereof and serviceable, amongst other uses, particularly in the construction of air crafts of various kinds, thus for example especially suitable for light forms of 15 structures, as in connection with flying machines. The novel unit according to the invention has a U-shaped or channelled cross-section, preferably with arcuate cross web curved in such a manner as to merge into the 20 straight side walls. A unit of the kind referred to does not break off abruptly at the free edges of the flanges, which for their part are as usual disposed to either side of the web, but continues along said edges, thus 25 forming additional outer flanges. These outside flanges are outwardly inclined symmetrically from the edge, where they are bent off, towards the central plane of the original U-shaped section, and serve to secure 30 the said section to other members. They thus constitute the simplest and most complete substitute imaginable for flat or curved angle sections, such as were hitherto required to establish a reliable hollow connection 35 between the channelled bar and the surface counterposed. The process of manufacture, as well as the use of the improved section rods will be rendered specially favorable, by their being produced of light 40 metal strips or thin sheet iron of great strength.

While the outside flanges primarily serve to establish a connection to wall portions, the inside flanges, disposed between the former and the web, readily admit of the formation of frames, lattice work constructions, points of intersection and the like, disposed at right angles to the wall portions.

The improved structure offers particular 50 advantages in its application to floats, boats, and hulls of aircraft, since this is a case where considerable lightness of weight and good resisting capacity are of prime importance. By aid of a modified form of my 55 improved structure, a float may be constructed adaptable for hydroplanes, in the case of

which the outside flanges of the sectional units are always disposed along one and the same plane at right angles to the central plane, while, owing to their being connected to the wall portions of the float, the said flanges serve to unite these latter to the "open" or channelled sectional units, and thus enable the formation of closed hollow sections of particularly great resisting capacity. Considering that the outside flanges embrace a broad portion of the float wall surface, there does not exist, even in the event of the height of the structure being considerable, any danger of the sectional 60 units collapsing in a lateral sense, while, on the other hand, the portions of the wall surface embraced by the outer flanges are thoroughly reinforced in consequence.

In case the float structure is to be subjected to particularly heavy strains, the outer wall is provided on one of its sides with a series of continuous transverse braces, and on the other side, with uninterrupted longitudinal braces. As a result of the peculiar 75 form given to the sectional units, the method of joining the series of frames, which are disposed independently of each other, with the wall portion of the float, is rendered very simple. In this improved structure the 80 seams are done away with which would otherwise be formed at the numerous points of intersection on the longitudinal and transverse frames being arranged along one plane.

Several structures embodying the subject matter of my invention are disclosed in the accompanying drawings forming part of this specification. In the drawings—

Figs. 1 to 3 show perspective views of the 95 three forms of my improved structural units,

Figs. 4 and 5 the angle joint in a side elevation and front elevation, partly in section, respectively, and

Figs. 6 and 7 are a cross-section and a longitudinal section, respectively, of a float provided with a bulkhead.

In the structures according to Figs. 1 and 2, both the web *a* and the inside flange *b*, as 105 also the outside flange *c* constitute uniformly disposed strips. Notwithstanding, as will be observed by reference to Fig. 3, certain of these strips (principally the inside flange *b*) may also be provided with apertures or 110 perforations in order to obtain a further reduction of weight.

In the case of the angle joint according to Figs. 4 and 5, the ends of the two structural units A and B are caused to meet with their ends cut off at an angle of 45° , so as to form the sides of a right angle. A corner scarf C embraces the channelled section proper, and is riveted to the inside flange b. The outside flanges c, disposed on the outer face of the aforesaid angle, are surrounded by a wall plate D, to which they are also secured by rivets.

In the case of the all-round enclosed float according to Figs. 6 and 7, E constitutes the surrounding outer wall. The inside space is divided by means of transverse bulkheads F into different compartments. The transverse bracing frames G, H, J, disposed along the outside shell E are brought in contact with this latter by means of their outside flanges c, and are riveted to said shell in the manner disclosed by Figs. 4 and 5, mutual stiffening and bracing both of the structural units as well as of the shell being produced by this connection. The corner joints are effected on the one hand by aid of scarf plates K uniting the inside flanges b which abut against each other, and on the other hand by means of a continuously extending transverse bulkhead wall F that, in each case, replaces the scarf plates. In order to brace the whole structure to an improved degree, there are arranged three diagonal struts or stays L, running from the center of the deck frame G to the free corners of the bulkhead, which are riveted to this latter by aid of the outside flange c and to the preferably somewhat projecting scarf plates K' by means of webs a. The outer face of the bottom of the outer wall or shell E, is

provided with longitudinal frames M fixed to said wall or shell by means of their outside flanges c. The deck structures G are connected to the bottom structures J by means of the vertical structural units H which are angularly connected to each other by means of the elbow scarfs and scarf plates K, K' respectively. The diagonal struts or stays L may, if desired, be also replaced by other sectional forms, say, for example, common U-shaped or channelled sections. However, seeing that these sections are open, the stability obtained would be essentially less, while the riveting operation would be rendered more difficult.

I claim:—

1. Sheet metal float for aircraft comprising in combination, a flanged substantially quadrangular channel iron frame, flanged metal channel braces extending from one side of said frame to the centre and corners of the opposite side and metal plates extending substantially at right angles to and connected with the four sides of said frame to form a braced substantially prismatic body.

2. Sheet metal float for aircraft comprising in combination, a flanged substantially quadrangular channel iron frame, flanged metal channel braces extending from one side of said frame to the centre and corners of the opposite side, metal plates extending substantially at right angles to and connected with the four sides of said frame to form a braced, substantially prismatic body and flanged metal channels connected with and extending lengthwise across the outer surface of one of said plates.

In testimony whereof I affix my signature.
CLAUDIUS DORNIER.
